(57) **CLAIM**

The ornamental design for a wash place unit, as shown and described.

DESCRIPTION

FIG. 1 is a front, left side and bottom perspective view of a wash place unit according to our new design.
FIG. 2 is a front elevational view of the wash place unit of FIG. 1.
FIG. 3 is a rear elevational view of the wash place unit of FIG. 1.
FIG. 4 is a right side elevational view of the wash place unit of FIG. 1.
FIG. 5 is a left side elevational view of the wash place unit of FIG. 1.
FIG. 6 is a top plan view of the wash place unit of FIG. 1.
FIG. 7 is a bottom plan view of the wash place unit of FIG. 1.
FIG. 8 is a front, left side and bottom perspective view of a second embodiment of a wash place unit.
FIG. 9 is a front elevational view of the wash place unit of FIG. 8.
FIG. 10 is a rear elevational view of the wash place unit of FIG. 8.
FIG. 11 is a right side elevational view of the wash place unit of FIG. 8.
FIG. 12 is a left side elevational view of the wash place unit of FIG. 8.
FIG. 13 is a top plan view of the wash place unit of FIG. 8.
FIG. 14 is a bottom plan view of the wash place unit of FIG. 8.
FIG. 15 is a front side elevational view of a third embodiment of a wash place unit above a wash basin, with the left side and the top forming no part of the claimed design.
FIG. 16 is a right side elevational view of the wash place unit positioned above a wash basin of FIG. 15.
FIG. 17 is a front side elevational view of a fourth embodiment of a wash place unit above a wash basin, with the left side and the top forming no part of the claimed design; and, FIG. 18 is a right side elevational view of the wash place unit positioned above a wash basin of FIG. 17.
The broken lines illustrate portions of the wash place unit and/or the environment that form no part of the claimed design.

1 Claim, 14 Drawing Sheets
